Arthur Block Inventor
By his Attorney
Mark J. Kent

UNITED STATES PATENT OFFICE.

ARTHUR BLOCH, OF PHILADELPHIA, PENNSYLVANIA.

OIL-CIRCULATION SIGNAL.

Application filed April 19, 1921. Serial No. 462,736.

To all whom it may concern:

Be it known that I, ARTHUR BLOCH, a citizen of the United States, residing at Philadelphia, in the county of Philadelphia and State of Pennsylvania, have invented certain new and useful Improvements in Oil-Circulation Signals, of which the following is a specification.

My invention has for its objects to provide a simple and efficient signal device for oil distributing or other circulating systems which will be relatively inexpensive and easily installed and which can be relied upon to give a definite warning signal when some failure occurs in the circulating system.

The invention involves a number of novel features of construction, combinations and arrangements of parts as will be clear from the following specification which is to be read in conjunction with the drawing accompanying and forming a part of the same and wherein the invention is illustrated embodied in a concrete practical form.

Figures 1 and 2 in the drawing referred to are central sectional views of the device, the first showing the relative position of the parts when there is pressure in the oil circulating system, and the latter illustrating operation of the parts when the pressure fails.

Figures 3 and 4 are plan and side views respectively of the pressure actuated circuit breaker.

In the present embodiment of the invention the entire apparatus is carried by and housed within a casing or shell 5 having an outstanding flange 6 by which the device may be located in an instrument board or the like. This casing is shown as divided by a partition 7 into a lamp housing 8 and a circuit breaker chamber 9.

Within the lamp housing, there is provided a suitable socket 10 for the lamp 11 and this end of the casing is shown as closed by a glass or lens 12 secured by a screw flange 13, a suitable gasket 14 being interposed between the glass and the end of the housing.

The chamber in the other end of the casing is closed by a plug 15 having a flange screw threaded at 16 to fit the interiorly screw threaded lower end of the casing. This plug has an inlet 17 for the oil or other circulating pipe 18 and carries a pressure actuated element shown in the form of

a piston or plunger 19 operating in a cylindrical bore 20 in the upper face of the plug.

This pressure element is shown as operating directly on the arm 21 of the circuit breaker which is pivoted on the upper face of the plug at 22 and carries at its free end a contact 23 for engagement with a relatively stationary contact 24 supported in an insulating bushing 25.

The contact carrying lever 21 is provided at its upper face with a conducting strip 26 extending from the contact 23 to the end of a coiled spring 27 which seats within and forces the metallic contact thimble 28 up into engagement with the center contact 29 of the lamp. This contact sleeve or thimble operates within an insulating bushing 30 in the horizontal partition 7.

The lamp is suitably connected in circuit usually by means of a wire extended from the insulated contact 24 to a battery or other source of energy, the circuit being completed by "grounding" the metallic casing 30 and the other side of the battery. When sufficient pressure is present in the oil circulating system, the contact lever 21 will be lifted by the pressure operated element so as to break the lamp circuit across the contacts 23, 24. When for any reason the pressure fails or falls below a predetermined force, the pressure operated element will drop back as in Figure 2 and allow the spring 27 to force back the contact lever 21 and bring the contacts into engagement. This will close the lamp circuit and thereby give a visual signal, indicating that the pressure has failed.

The construction disclosed is particularly desirable in that the device may be easily installed, it simply being necessary to provide a cylindrical opening large enough to receive the barrel or casing and to then fit the casing within such opening.

The plug in the lower end of the device may be easily removed at any time by simply unscrewing it. The spring 27, it will be observed, serves dual functions in that it operates to press the center lamp contact 105 into engagement with the lamp and also to return the contact lever to the circuit closed position. To prevent breakage or displacement of the parts when the plug is screwed into or out of the end of the casing, I have shown the contact strip on the upper face of the switch lever 21 as provided with a

centrally located stud 31 fitting the lower end of the coiled spring and serving thereby to hold the spring centralized during the turning of the plug.

5 It will be understood that the structure may be modified in various respects without departure from the true spirit and scope of the invention as herein defined and claimed. For instance, if found desirable, the relatively fixed contact 24 might be provided 10 at the outside of the plug with a binding post or suitable terminal device for the attachment of the circuit wire.

What I claim is:

15 1. In an apparatus of the character disclosed, a casing, a support detachably mounted on said casing, a lever pivoted on said support, a contact carried by said lever, a relatively stationary contact on the support for engagement by the lever-carried contact, a pressure actuated element on the support beneath the lever for operating the lever in one direction, a spring bearing on said lever and adapted to move the same 20 in the opposite direction, a signal element, means mounting said element in said casing, and means forming an electrical connection between said lever-carried-contact and said signal element including a spring bearing 25 on said lever and adapted to move it in the opposite direction.

2. In apparatus of the character disclosed, a casing having a partition dividing the same into a signal and a switch chamber, 30 a lamp socket on said partition and extending into the signal chamber, a lamp contact plunger operating in the partition and in contact with said socket, a relatively movable and a stationary switch contact in the 35 switch chamber, a spring engaged between the contact plunger and the relatively movable switch member for operating said plunger and said movable switch member and a pressure actuated element operatively

engageable with the movable switch member. 45

3. In apparatus of the character disclosed, a casing having a partition dividing the same into a signal and a switch chamber, a lamp socket on said partition and extending 50 into the signal chamber, a lamp contact plunger operating in the partition and in contact with said socket, a relatively movable and a stationary switch member in the switch chamber, a spring engaged between 55 the contact plunger and the relatively movable switch member for operating said plunger and said movable switch member, a pressure actuated element operatively engageable 60 with the movable switch member, said movable switch member including a pivoted switch lever carrying a contact, a conducting strip connected with said contact and a stud carried by said strip and engaging one end of the spring aforesaid. 65

4. In apparatus of the character disclosed a casing having a partition dividing the same into a signal and a switch chamber, a lamp socket on said partition and extending 70 into the signal chamber, a lamp contact plunger operating in the partition and in contact with said socket, a relatively movable and a stationary switch contact in the switch chamber, a spring engaged between 75 the contact plunger and the relatively movable switch member for operating said plunger and said movable switch member and a pressure actuated element operatively engageable with the movable switch member, the switch contacts and the pressure 80 actuated element being mounted on a supporting member having a screw threaded connection with the casing and the movable switch element having a centrally located stud for guiding the end of the spring. 85

In testimony whereof I affix my signature.

ARTHUR BLOCH.
